UNITED STATES PATENT OFFICE.

RAY P. JACKSON, OF EDGEWOOD PARK, PENNSYLVANIA, ASSIGNOR TO WESTINGHOUSE ELECTRIC & MANUFACTURING COMPANY, A CORPORATION OF PENNSYLVANIA.

INSULATOR.

Application filed June 3, 1921. Serial No. 474,728.

My invention relates to insulators and particularly to insulators of the link type.

One object of my invention is to provide an insulator of the above indicated character, that shall have portions so shaped to conform to the flow lines of the electrostatic field thereof and surfaces so disposed at right angles to the flow lines of said field as to improve the operating characteristics thereof.

A second object of my invention is to provide a link-type insulator of refractory material that shall comprise walls and other portions of such relation and uniform thickness as to avoid the defects sometimes caused in unequal masses of refractory material during the firing thereof.

A further object of my invention is to provide an insulator of the link type that shall comprise a substantially spherical main central body portion from which a single integral petticoat, extending in one general direction therefrom, may have an outer surface approaching a portion of the sphere in substantially tangential relation thereto.

In Patent No. 1,129,520, granted to the Westinghouse Electric and Manufacturing Company, February 23, 1915, upon an application filed by K. C. Randall, S. W. Farnsworth and C. LeG. Fortescue, is set forth the principle that an insulating body having its surfaces conforming to the flow lines of the electrostatic field surrounding it provides substantially the same insulating value as air.

This patent also shows an insulator having an equipotential surface or, in other words, a surface that is, at every point, substantially at right angles to the flow lines of said field.

In Patent No. 1,374,998, granted to the Westinghouse Electric and Manufacturing Company, April 19, 1921, upon an application filed by C. LeG. Fortescue and G. I. Gilchrest, the features of field-conforming or flow-line surfaces and equipotential surfaces are shown and described in connection with an insulator of the pin type. To the best of my knowledge, these features have never been embodied in an insulator of the link type.

In the process of firing a porcelain insulator, adjacent masses of porcelain of different volumes sometimes cause fissures and weak portions, at the positions of joinder

between them, by reason of unequal expansion. These fissures or weak portions are frequently hidden in the body of the insulator and certain of them, while initially of insufficient magnitude to cause failure under electrical and mechanical tests, develop under different temperature conditions, while in service, to cause failure.

A refractory insulator of the link type, by reason of its peculiar shape, is particularly subject to the defects caused by uneven masses and such an insulator, which avoids these defects and, at the same time, embodies equipotential and flow-line surfaces, presents a different problem than an insulator of the pin or other types.

In practicing my invention, I provide a refractory insulator of the link type in which a petticoat portion of substantially paraboloid bowl shape is, by reason of its form and dimensions, disposed substantially everywhere on its surface at right angles to the flow lines of its electrostatic field. A substantially spherical body portion, integral with the petticoat portion, is of such uniform mass relation to the petticoat as to avoid the above mentioned defects and is, also, shaped to have portions conforming to the flow lines of the electrostatic field.

Figure 1 of the accompanying drawing, 85 is a side view, partially in elevation and partially in section, of a pair of insulator units embodying my invention, and

Fig. 2 is a sectional view of one of the units of Fig. 1 taken at right angles thereto. 90

An insulator, of the link-type embodying my invention, comprises, in general, a plurality of preferably refractory or porcelain units 1 constituting the alternate links in a flexible series, similar to an ordinary metal 95 chain, in which the other links are metal connecting devices 2. The latter, constituting no part of my present invention, will not be described in detail but they comprise preferably cylindrical rods or wires 3 bent 100 to U-shape and connected, at their free ends, to suitable members 4.

The electrostatic field surrounding a link-type insulator has been found by test to be substantially as shown by dotted lines in 105 connection with the upper unit of Fig. 1. This test consists in cutting an opening conforming to the central-plane contour of the insulator in a piece of cardboard or other member and placing the cardboard or other 110

member in the central plane of the insulator with the insulator and the cardboard in a horizontal plane. When mica flake particles are placed on the cardboard, and the metal 5 terminal or connecting members are submitted to a relatively great difference of potential, the mica flakes arrange themselves in accordance with the flow lines of the electrostatic field similarly to the arrangement 10 of iron filings in a magnetic field. The above test is a usual expedient for determining electrostatic fields but is described in detail to illustrate more effectively the reason 15 for the precise shape and dimensions of the insulator of my invention.

Accordingly, petticoat or surface-creepage portions 5, on the porcelain units 1, in order that they may have their upper surfaces 20 everywhere at right angles to the electrostatic field and that the insulator may have increased surface-creepage distance and reduced overall length, are each constructed to be of substantially paraboloid bowl shape having an outer edge 6 of a lateral radius 25 from the longitudinal axis of the insulator greater than the longitudinal depth of the bowl.

In order that the metal members 3 may 30 inter-link, similar to the links of an ordinary chain and be fully insulated from each other, the petticoats 5 are each provided with a central portion 7 of substantially semispherical form joined integrally to the inner surfaces 35 of the bowl or petticoat.

The bottom or closed end of the bowl or 40 petticoat, also being semi-spherical in outer contour, taken with the semi-spherical portion 7 as a single mass, form a main central mass or body portion of uniform substantially spherical form. The remainder 45 of the petticoat extends in one general direction from the central spherical mass and has its outer surface preferably approaching the central mass along lines that are substantially tangential thereto.

The above-described construction prevents 50 the concentration of electrostatic stresses and the consequent flash-over at voltages below that of the full ability of the insulator to withstand, as set forth in the above mentioned patents. Further, the petticoats 5, being constructed of uniform thickness throughout and the main body portion being of symmetrical form, the likelihood of de-

fects, caused during the firing operation by 55 uneven masses, is materially reduced.

The portion 7 is symmetrically flared at its intersection with the petticoat to better distribute mechanical stresses between it and the bowl but is, over the major portion of 60 its surface, shaped to conform to the electrostatic flow lines, as indicated by the surfaces 8. A space 9, between the portion 7 and the inner bottom surface of the bowl, constitutes an opening for the reception of the lower 65 metal member 3 and the opening 10 through the portion 7, which is provided for the reception of the upper metal member 2, is centrally disposed in the portion 7 to render the 70 walls of the latter uniform and of such mass or thickness with respect to the bowl as to prevent the formation of fissures during the firing operation.

An insulator constructed in accordance 75 with my invention is not only formed to provide equipotential and flowline surfaces but, also, to render the mass thereof of such symmetrical form and uniform thickness as to prevent expansion defects during firing and it is the combination of these two features 80 and the individual advantages of each which render the insulator more durable and effective.

While I have shown and described a particular form of my invention, changes may 85 be effected therein, without departing from the spirit and scope thereof, as set forth in the appended claims.

I claim as my invention:

1. An insulator comprising an insulating 90 member having a portion of substantially paraboloid shape, the inner and outer surfaces of which are spaced substantially the same distance throughout, entirely within the paraboloid contour, and a substantially 95 spherical body portion having a central opening and walls of uniform thickness.

2. A link insulator comprising a central substantially spherical body portion and a single petticoat portion intercepting the 100 same and extending in one general direction therefrom, the walls of said portions being of substantially uniform thickness throughout, except at positions adjacent to intercepting surfaces thereof.

In testimony wherof, I have hereunto subscribed my name this 9th day of May, 1921.

RAY P. JACKSON.
